UNITED STATES PATENT OFFICE.

WILLIAM L. KELLOGG, OF MOUND CITY, ILLINOIS.

STAVE-MAKING MACHINE.

SPECIFICATION forming part of Letters Patent No. 399,670, dated March 19, 1889.

Application filed September 29, 1888. Serial No. 286,769. (No model.)

To all whom it may concern:

Be it known that I, WILLIAM L. KELLOGG, a citizen of the United States, residing at Mound City, in the county of Pulaski and 5 State of Illinois, have invented certain new and useful Improvements in Stave-Making Machines, of which the following is a specification.

In the manufacture of staves for liquor 10 kegs, barrels, &c., which are preferably formed with thick ends and hollowed out in the middle to a point near each end, it has been usual to employ two or three separate machines in working down the rough block to the finished 15 stave.

The object of my said invention is to provide a single machine adapted to receive the rough block as it comes from the yard and work it down to a finished stave by a single 20 operation, and also one which will turn out the staves in the most perfect and desired form for use, as will be hereinafter more particularly described and claimed.

Referring to the accompanying drawings, 25 which are made a part hereof, and on which similar letters of reference indicate similar parts, Figure 1 is a perspective view of a machine embodying my said invention; Fig. 2, a view of the rear side of the said machine in 30 elevation; Fig. 3, a longitudinal central section through the same, looking at the parts from the front of the machine; and Fig. 4, a detail sectional view on the dotted line 4-4 in Fig. 3.

In said drawings the portions marked A represent the frame-work of the machine; B B' B², the bed-plate thereof; C, the cutter-head for dressing the under side of the stave; C' C² C³, the cutter-heads for dressing the top or inner surface; D, an endless feeding-apron; E, a shaft carrying a line of gearing suitably arranged to connect with and operate the several parts of this machine; F, a power-belt for driving the same; G' G² G³, a series of "dead" 40 rolls arranged to hold and guide the staves during their passage through the machine, and G⁴ G⁵ "live" rolls for feeding and guiding the staves under the last cutter-head and out of the machine.

The frame-work A is any suitable frame-work for supporting and carrying the various parts and gearing of the machine, being pro-

vided with suitable bearings for the several shafts, as shown.

The main portion B of the bed-plate, or that 55 portion from the cutter-head C to the incline, is formed with a concave surface which corresponds substantially with the shape of the stave when finished. At a point substantially beneath the finishing cutter-head a 60 notch, b, is formed, into which the end of the stave drops when it should leave the knife, as will be hereinafter more particularly described. Just in front of the said notch the bed-plate is extended out into an upwardly- 65 inclined part, B', also formed concave in cross-section. This portion starts with an abrupt incline, formed, preferably, by a roller, b', so journaled and arranged as to project up through and in effect operate as a part of the 70 bed-plate, and serves to elevate the stave against the cutter-head C³. From the top of the roll said part B' is inclined upwardly with the degree of incline necessary to hold the stave in the desired position in relation 75 to said cutter-head C³, the pitch being somewhat abrupt at the extreme end to allow the other end of the stave to drop into the notch b. The portion B² of the bed-plate extends from the cutter-head C to the 80 rear end of the machine, it being that portion which first receives the block. This portion is formed with a convex upper surface, instead of concave, in order that the block may be more readily adjusted in exactly the position 85 in relation to the cutter-heads which will best suit its grain, surface, or any other peculiar conditions, and produce the best quality of manufacture which it is possible to obtain. Said portion is also adjustably mounted by 90 means of short arms, b², pivoted to the sides thereof and to the sides of the frame-work, a handle, b³, being secured to one side and extended out through a curved slot in the side of said frame-work for adjusting said table 95 back and forth to bring the block to the desired elevation in relation to the cutter-head C.

The cutter-head C is mounted upon a suitable shaft journaled in appropriate bearings on the frame-work and extends up through 100 the bed-plate, between the portions B and B², that distance which is desired to dress down the back or outside surface of the stave. Its knives are formed with concave cutting-edges,

the degree of curvature being that at which it is desired to form the stave.

- The cutter-heads C', C², and C³ are arranged on a shaft, C⁴, which is journaled in suitable bearings formed in the brackets c, secured above the bed-plate at each end thereof. The cutter-head C' is of a smaller diameter than C², it being the first to operate upon the top of the stave and take off the first thickness.
- 10 The head C² is arranged to follow the head C' and cut the block down to the thickness which it is desired the stave shall have at its ends. The head C³ is mounted so that the block will not come in contact therewith until it has been raised by the abrupt incline or roller b', and is arranged substantially that distance behind said portion which is equal to the length of the part of the stave which it is desired to leave thick. It is also slightly in advance of the notch b in the bed-plate, so that the end of the stave will drop away therefrom before the end is reached, and leave a thick portion of the desired length.
- 15 The endless apron D consists of chain belts mounted on sprocket-wheels d, which are mounted on suitable shafts journaled in the frame-work, one of which extends out and is provided with a suitable gear-wheel which is connected to the driving-power. They carry 20 at suitable intervals cross-bars D', which are formed with points on their front surfaces to engage with the end of the stave-block. Said cross-bars are preferably formed in the shape of angle-irons and pivoted near the 25 front corners of the horizontal portion in suitable bearings on the chain belts, and behind said pivots are formed with outwardly-projecting arms d', adapted to engage with grooves or ways a, formed in the sides of 30 the frame while they are traveling forward, and thus maintain said cross-bars, which serve the purpose of "dogs," in an upright position while in use. When they reach the 35 front of the bed-plate B², they leave said ways and are carried around, under, and to the rear of said part, when they again engage with said ways by passing up through suitable notches, a', communicating therewith, as will be readily understood.
- 40 The shaft E and the line of gearing which it carries are driven from any convenient power by the belt F, and are of a common and well-known construction.

- The rolls G G' G² G³ are arranged to hold 45 the stave down to the bed-plate during its passage through the machine, being journaled in spring-mounted bearings in suitably-arranged posts along the sides of the frame A. The posts in which the bearings for the roll 50 G³ are mounted are also preferably secured in longitudinal slots, as indicated in Fig. 1, and the adjustment of said roll longitudinally of the machine thus provided for, which is desirable when a change is made from blocks of 55 one length to those of another, as it is intended that this roll shall bear upon and firmly clamp the rear end of the block to the bed-plate at

the time when the cutter-head C³ commences to operate upon its other end.

The rolls G⁴ and G⁵ are driven by means of 70 cog gear-wheels on one end of their journals, which mesh with a chain of gearing driven from the shaft E, as will be presently described. The roll G⁴ operates to hold the stave down and feed it forward to the finishing cutter-head C², and the roll G⁵ operates to steady and hold down the end of the stave as it comes through and at the same time carry it up over the incline B' and out of the machine. Said rolls G⁴ and G⁵ are also journaled 75 in spring-mounted bearings, as are the other rolls just described.

The arrangement and operation of the gearing for driving the various parts of this machine are very simple, and may of course be 80 varied as found desirable without departing from my invention. In the arrangement shown the shaft E, as before described, is driven from any convenient power through 85 the belt F. The feeding-apron D is driven 90 from said shaft E through the belt 1, which passes over the band-pulley 2, mounted on a short shaft journaled in suitable bearings in the side of the frame, and connected by a chain of gearing to the cog-wheel 3 on the end of 95 the front shaft of said feeding-apron. The shaft carrying the cutter-head C is driven from said shaft E through the belt 4, which engages with the pulley 5 on the counter-shaft 6 at the front of the machine, which is 100 geared to said shaft of the cutter-head C by two belts, 7, running over suitable pulleys on 105 said shafts, one being arranged on each side of the machine. The shaft or mandrel C⁴, on which the cutter-heads C', C², and C³ are 110 mounted, is driven from the shaft E by a belt, 8, which engages with the band-pulley 9 thereon, and the rolls b' and G⁴ and G⁵ are 115 driven from said shaft E by the belt 10, which engages with the pulley 11, mounted on a 120 short shaft journaled in the frame A, which is provided with a cog gear-wheel, 12, which meshes with the cog gear-wheel 13 on the shaft of the roll G⁴, and through a connecting gear-wheel, 14, drives the gear-wheel 15 on 125 the shaft of the roll b', which in turn meshes with and drives the gear-wheel 16 on the shaft of the roll G⁵, the direction in which the several wheels and rolls are driven being indicated by arrows.

The operation of my said invention is as follows: The rough stave-block as it comes from the yard is placed upon the adjustable bed-plate B² at the rear end of the machine in front of one of the cross-bars D', the points 130 on the front side of which engage with its rear end and force it forward under the rolls G and G' and against the cutter-head C, which operates to dress its under side in the manner desired, the adjustable bed-plate B² being of course first adjusted to a height to suit the thickness and conditions of the surface of the stave-block. The block is then fed forward, the cutter-head C' operating to take off

a portion of its upper surface, and the cutter-head C^2 being arranged to take off the remainder of the surplus thickness, the block after it leaves said head being of the thickness which it is desired that the finished stave shall be at its ends, and also of the curvature in cross-section desired. The stave is then carried forward under the rolls G^3 and G^4 , which feed it forward under the cutter-head C^3 , which is arranged so that the space between it and the bed-plate will be greater than the thickness of the stave, and thus the end of the stave passes under said cutter-head until it strikes the roller b' , which elevates it abruptly to within reach of said cutter-head, which thus commences to operate thereon the desired distance from its end. After the abrupt incline or roll b' has elevated the end until the cutter-head is taking the depth of cut desired the gradual incline operates to maintain the stave in the desired relative position to said cutter-head C^3 until its end has passed to the notch b , formed in the bed-plate, into which it drops out of reach of the cutter-head in time to leave the desired length of the end thick, as before described, while its center is cut out evenly to a point exactly the same distance from each end, and the shoulder at each end is formed concave—a shape which will allow the stave to spring up to or even into said shoulders, and at the same time contain no surplus wood. A stave is thus formed which will bend uniformly from end to end, and one which, by reason of its substantially equal thickness throughout all corresponding portions of its length and its concave shoulders, will not break while being made into the manufacture for which they are intended. The labor required to operate the usual machines for dressing down the staves before being put through the finishing-machine is also saved, and a very complete and perfect machine for the purpose thus provided.

In Fig. 3 the different forms of the block during the different steps of the process are illustrated. At the rear is shown a block which has passed partly through between the cutter-heads C , C' , and C^2 . In front of this is a block that has been dressed on its rear side by said head C , and on its inner side by said heads C' and C^2 to the form and thickness desired, and has passed to the position it occupies just before being forced up into contact with the head C^3 by the abrupt incline or roller b' , and the form of the stave, after passing under said head C^3 , is indicated

in dotted lines, it being ready to be jointed and made into the manufacture.

Having thus fully described my said invention, what I claim as new, and desire to secure by Letters Patent, is—

1. In a machine for manufacturing staves, the combination of the frame-work, a longitudinal shaft arranged above said frame-work and carrying a cutter-head, a bed-plate, formed with a notch beneath said cutter-head, into which the rear end of the stave may fall as it leaves said cutter-head, and an inclined end for guiding said stave out of the machine, substantially as set forth.

2. The combination, in a machine for dressing staves, of the frame, the cutter-head arranged to operate transversely of said bed-plate, and said bed-plate formed with a short abrupt incline in front of said cutter-head, and a longer incline terminating in another abrupt incline beyond said short inclines, substantially as set forth.

3. In a stave-dressing machine, the combination of the frame-work, a bed-plate mounted thereon formed with a notch, into which the rear end of the stave may drop as it leaves the cutter-head, an upwardly-inclined end beyond said notch, and a cutter mounted above and arranged to operate transversely of said bed-plate and above said notch, substantially as described, and for the purposes specified.

4. In a machine for dressing staves, the combination of the frame, a shaft journaled above said frame and extending longitudinally thereof, a series of cutter-heads thereon arranged to cut to different depths, and suitable feeding and driving mechanism, substantially as set forth.

5. In a machine for dressing staves, the combination of the frame, the bed-plate for guiding the staves, a cutter-head formed to dress one side of said stave, mounted beneath said bed-plate, a series of cutter-heads arranged to cut into the block different depths for dressing the other side of said stave mounted above said bed-plate, and an adjustable table for receiving the stave-blocks and suitable mechanism for carrying them forward, substantially as set forth.

In witness whereof I have hereunto set my hand and seal, at Indianapolis, Indiana, this 22d day of September, A. D. 1888.

WILLIAM L. KELLOGG. [L. S.]
